(57) **CLAIM**

The ornamental design for a wallet for compact discs, shown and described.

DESCRIPTION

FIG. 1 is a front perspective view of a wallet for compact discs showing my new design; the broken lines showing a fastener-pull throughout the views representing a portion of the design that forms no part of the claim;

FIG. 2 is a top perspective view thereof shown in an open position. The broken lines showing interior details represent portions of the design that form no part of the claim.

FIG. 3 is a front elevation view of the invention illustrated in FIG. 1;

FIG. 4 is a rear elevation view of the invention illustrated in FIG. 1;

FIG. 5 is a right elevation view of the invention illustrated in FIG. 1;

FIG. 6 is a left elevation view of the invention illustrated in FIG. 1;

FIG. 7 is a top plan view of the invention illustrated in FIG. 1; and,

FIG. 8 is a bottom plan view of the invention illustrated in FIG. 1.

The top and bottom broken lines immediately adjacent to the shaded surfaces in FIG. 2 define the boundaries of the design. The broken lines themselves, as well as the broken lines in between them form no part of the claim.
